CLAIM

The ornamental design for mini vertical blinds, as shown and described.

DESCRIPTION

FIG. 1 is a front elevational view of the mini vertical blinds showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The blinds shown in FIGS. 1-4 are shown broken away to indicate indeterminate length.
